(57) **CLAIM**

I claim the ornamental design for a case for reading glasses, as shown and described.

DESCRIPTION

FIG. 1 is an isometric view of a case for reading glasses showing my new design;

FIG. 2 is a top, plan view of the case for reading glasses of FIG. 1;

FIG. 3 is a bottom view of the case for reading glasses of FIG. 1;

FIG. 4 is a rear view of the case for reading glasses of FIG. 1;

FIG. 5 is a side view of the case for reading glasses of FIG. 1;

FIG. 6 is a front view of the case for reading glasses of FIG. 1;

FIG. 7 is an isometric view of an alternate embodiment of the design shown in FIG. 1;

FIG. 8 is a top, plan view of the case for reading glasses of FIG. 7;

FIG. 9 is a bottom view of the case for reading glasses of FIG. 7;

FIG. 10 is a rear view of the case for reading glasses of FIG. 7;

FIG. 11 is a side view of the case for reading glasses of FIG. 7; and,

FIG. 12 is a front view of the case for reading glasses of FIG. 7.
